TOY LANDING CRAFT

William C. Peterson, 31 Water St., Claremont, N.H.

Filed Jan. 3, 1964, Ser. No. 78,057

Term of patent 7 years

(Cl. D34—15)

FIG. 1

FIG. 2

FIG. 3

FIGURE 1 is a top plan view of a toy landing craft showing my new design;

FIGURE 2 is a side elevation view, both sides being the same;

FIGURE 3 is a perspective view with the back dropped to a substantially horizontal position.

The outer portion of the drop back is plain and unornamented.

I claim:

The ornamental design for a toy landing craft, as shown and described.
